FIG. 5.

UNITED STATES PATENT OFFICE.

OSCAR C. KAVLE, OF SYRACUSE, NEW YORK, ASSIGNOR TO E. FREDERICKS, INC., OF NEW YORK, N. Y., A CORPORATION OF NEW YORK.

HAIR CURLER.

Application filed March 20, 1924. Serial No. 700,507.

To all whom it may concern:

Be it known that I, OSCAR C. KAVLE, a citizen of the United States of America, of Syracuse, in the county of Onondaga, in the State of New York, have invented new and useful Improvements in Hair Curlers, of which the following, taken in connection with the accompanying drawings, is a full, clear, and exact description.

10 This invention relates to a hair curler involving the use of an elongated tubular section and relatively short end sections connected to each other by means of a rod extending through the tube whereby the 15 tubular section and end sections may be relatively rotated in one direction.

I am aware that devices of this character having opposite end heads rotatably mounted at the opposite ends of a tube and connected through by means of a rod, have heretofore been proposed, but in those devices the slotted head for receiving the binding cord terminates against the adjacent end of the tube where it is held against end- 25 wise displacement by the connecting rod extending through the tube without any means except the rod for holding it against radial movement.

This radial movement is detrimental to 30 devices of this character in that it allows strands of the hair to be caught in the joint and broken by the relative turning of the head and tube and also produces more or less uneven pulling of those strands at the 35 roots, all of which is irritating to the party operated upon and prevents a perfect waving or curling of the hair.

One of the objects of this invention is to 40 provide the slotted head with a relatively long journal bearing within the adjacent end of the tube to hold said head and tube against relative radial movement and thereby to maintain a sufficiently smooth close fitting end-thrust bearing between the head 45 and tube to prevent strands of the hair from passing thereinto.

Furthermore, in the known devices of this character, the relative rotary movement of the slotted head and tube in one direction

and the prevention of its rotation in the 50 opposite direction is accomplished either by means of a ratchet and pawl action or by positive locks operable under spring tension which require their release before the relative turning movement can be effected, 55 whereas in applicant's device, the object is to permit this relative turning movement in one direction and to prevent such relative movement in the opposite direction without displacing any locking devices or without 60 relative axial movement of the relatively rotatable parts and thereby to assist in maintaining the smooth and tight end-thrust joint between the slotted member and the tube. 65

Other objects and uses relating to specific parts of the device will be brought out in the following description.

In the drawings:—

Figure 1 is a face view of a hair curling 70 device embodying certain features of my invention.

Figure 2 is an enlarged longitudinal sectional view, partly broken away, taken on line 2—2, Figure 1. 75

Figures 3 and 4 are transverse sectional views taken in the planes of lines 3—3 and 4—4, Figure 2.

Figure 5 is a longitudinal sectional view of a modified form of a hair curler, partly 80 broken away.

Figures 6 and 7 are transverse sectional views taken in the planes of lines 6—6, and 7—7, Figure 5.

The device shown in Figures 1 to 4 inclusive 85 comprises an elongated tube —1— of any suitable material having its exterior surface tapered from end to end, and opposite end heads —2— and —3— rotatably mounted on the corresponding ends of the tube —1— and operatively connected to each other by a connecting rod —4— extending centrally through the tube —1—.

A portion of the head —2— is rotatably mounted in the smaller end of the tube —1— 95 and extends axially some distance beyond the corresponding end of said tube, the external portion being of substantially the

same diameter as the adjacent end of the tube and provided with a diametrically extending slot —5— for receiving a binding cord commonly used for tying a bunch of hair together near the scalp preparatory to curling the same.

The outer ends of the arms of the bifurcated portion of the head —2— are preferably tapered or beveled to permit the cord 10 to be readily inserted into the slot —5— and also to permit it to pass readily through the strands of hair.

The tube —1— is provided with a central lengthwise bore concentric with its axis and 15 of greater diameter than the connecting rod —4—, the opposite ends of said bore being cylindrical but of unequal diameters, that in the smaller end being of less diameter than that of the larger end.

20 The head —2— is provided with a reduced axially elongated cylindrical shank —6— of substantially the same exterior diameter as that of the adjacent end of the tube —1— journaled for relative rotation, 25 the reduced end forming a shoulder —7— which closely fits against the adjacent end of the tube thereby forming a smooth closed end-thrust joint between those parts to prevent any possibility of strands of hair 30 becoming entangled or caught therein.

The reduced shank —6— closely fits within the adjacent end of the tube —1— to prevent relative lateral or radial movement of the head —2— and tube —1— and at the 35 same time permitting those parts to be relatively turned when desired.

This shank —6— is provided with a central threaded socket —8— of the same 40 length as or less length than the distance between the inner end of the shank —6— and shoulder —7— for receiving the adjacent threaded end of the rod —4— which engages the end wall of the socket and thereby serves to lock the head —2— and rod —4— to each 45 other for simultaneous turning movement.

The periphery of the end of the tube —1— opposite that in which the head —2— is journaled is also cylindrical and upon this 50 cylindrical periphery is journaled the head —3— to permit relative rotary movement of the connected heads —2— and —3— and tube —1—.

The inner end of the head —3— which is journaled upon the periphery of the adjacent end of the tube —1— is provided 55 with a socket —9— of the same diameter as the exterior diameter of the adjacent end of the tube so as to establish a close turning fit between the tube and head which telescope with each other.

This socket extends outwardly some distance from the inner end of the head but is of less length than the head —3— thereby forming a shoulder —10— which abuts

against the adjacent end face of the tube 65 to limit the inward movement of the head —3—.

The end of the bore in the tube —1— adjacent the head —3— is enlarged to form an inner annular friction face —11— and a 70 shoulder —12— at the inner end of said friction face some distance from the corresponding end of the tube for receiving one end of a coil spring —13—.

The portion of the head —3— between 75 the shoulder —10— and the outer end of said head is bored to form an inner annular friction face —14— of the same diameter as the friction face —11— in the adjacent end of the tube —1— for receiving the outer end of the coil spring —13—, said bore forming a shoulder —15— some distance 80 from the adjacent end of the tube —1—.

The portion of the head —3— between 85 the shoulder —15— and the outer end of said head is provided with an additional bore —16— in which the adjacent end of the rod —4— is closely fitted and is secured to the outer end of the head —3— by a diametrically extending pin —17—, Figure 2.

The coil spring —13— is cylindrical and of the same exterior diameter as the interior diameter of the annular friction faces —11— and —14—, said spring being compressed 90 between the shoulders —12— and —15— so that its convolutions lie in close relation or in contact with one another thereby maintaining a uniform exterior diameter of the coil spring for frictional engagement with the annular friction faces —11— and —14—, 95 the ends of the spring being unattached and tensioned so as to spring against the adjacent annular friction faces —11— and —14— for permitting the relative rotation of the rod —4— with the heads —2— and —3— thereon and the tube —1— in one direction and frictionally preventing their 100 relative rotation in an opposite direction.

In assembling the heads upon the tube, the rod —4— is tightly screwed into the socket 110 —8— of the head —2— to lock those parts to each other for simultaneous rotation in the tube, as for example, in a clockwise direction relatively to said tube or to permit the tube to be turned in a counter-clockwise 115 direction relatively to the rod —4— and head —2— without liability of loosening the locking connection between the head and rod.

When the rod —4— and head —2— are 120 properly locked to each other, the head —3— is telescopically fitted upon a periphery of the adjacent end of the tube —1— with its shoulder —10— engaging the adjacent end of said tube after which the pin 125 —17— is inserted through the outer end of the head —3— and corresponding end of the rod —4— to lock those parts together against

relative rotation and at the same time to permit them to be rotated in a clockwise direction upon the adjacent end of the tube —1— or the tube may be rotated in a counter-clockwise direction within the adjacent end of the head —3— and upon the reduced portion of the head —2—.

The coil spring —13— is wound in such manner as to permit the relative rotations 10 of the heads and tube in one direction and to frictionally lock them against movement in a reverse direction.

In other words, when the various parts of the curling device are assembled in the manner described, any tendency to turn the heads —2— and —3— in a counter-clockwise direction relatively to the tube —1— would be resisted by the tendency of such turning movement to unwind the spring while the 20 opposite movement would tend to wind the spring and thereby permit the clockwise movement of the heads and rod relatively to the tube, or the tube might be turned freely in a counter-clockwise direction relatively to 25 the heads and rod.

The construction shown in Figures 5, 6 and 7 is somewhat similar to that shown in Figures 1 to 4 inclusive except that provision is made for yieldingly holding the head 30 —2— in end-thrust engagement with the corresponding end of the tube to take up wear and to maintain a smooth and tight end-thrust joint.

For this purpose, the rod is preferably 35 made in sections —4'— and —4''— arranged coaxially end to end and coupled together at their adjacent ends by a coupling —18— which is secured at one end to the inner end of the section —4''— by 40 means of a pin —19— and has its other end provided with an axially elongated slot —20— for receiving radial pins —21— on the adjacent end of the section —4'— thereby locking the two sections together but permitting their relative endwise movement.

In this modified construction the tube is 50 preferably composed of a relatively long section —1'— and a relatively shorter section —1''—, the larger end of the section —1'— being threaded externally while the inner end of the section —1''— is threaded internally for screw engagement with the externally threaded end of the section —1'—, the two sections being firmly secured together after the interior parts are 55 properly assembled in a manner presently described.

The rod sections —4'— and —4''— extend axially through both of the tube sections —1'— and —1''— while the coupling 60 —18— is preferably located wholly within the section —1'—.

The interior of the tube section —1'— is provided with an annular shoulder —22—

against which is seated a hardened washer 65 or equivalent bearing member —23— for receiving the adjacent end of a coil spring —24—, said washer being provided with a central opening through which the rod section —4''— extends.

This rod section is provided with a shoulder —25— between the coupling —18— and bearing member —23— and keyed to said rod section —4'— by a pin —26—, Figure 70 5 to form a bearing for the adjacent end 75 of the spring —24—.

This spring —24— is tensioned to press the rod section —4'— toward the coupling member —18— for holding the shoulder —7— firmly against the adjacent end of the 80 tube section —1'— to take up wear and to maintain a smooth and tight end thrust joint between the section —2— and the tube.

The outer end of the rod section —4''— is keyed to an end section —3'— by means 85 of a pin —17— whereby the turning of the head —3'— will impart a similar turning movement to the rod sections —4''— and —4'— and also to the head —2— which is secured to the rod section —4'— in a manner similar to that previously described for the construction shown in Figures 1 to 4 inclusive.

The inner end of the head —3'— is enlarged to form a shoulder —27— which 90 is engaged by another shoulder —28— on the outer end of the tube section —1''— for holding the head —3'— against outward axial displacement.

That is, the inner enlarged section of the 100 head —3'— is journaled within the adjacent end of the tube section —1''— and its reduced end extends outwardly through and beyond a central opening in the outer end of said tube section —1''— to be turned by 105 hand or by the application of a suitable tool thereto.

The outer end of the tube section —1'— and inner end of the head —3'— are provided respectively with inner annular friction faces —11'— and —14'— for receiving 110 and engaging the periphery of a coil spring —13'—.

These annular friction faces are of the same diameter and are arranged coaxially 115 end to end so that a portion of the periphery of the spring engages one friction face and another portion the other friction face, said spring being tensioned to frictionally engage both faces thereby permitting the connecting rod with the heads thereon and tube sections to be turned relatively to each other in one direction and preventing their relative turning movement in the opposite direction in a manner similar to that previously 120 described for the spring —13—.

In order to form the friction faces —11'— and —14'—, the adjacent ends of the tube

section —1'— and head —3'— are provided with coaxial sockets in which the spring —13'— is located and engaged with the end walls of said sockets.

5 When the parts within the tubular sections are properly assembled and the tubular sections are secured to each other, the spring —13'— will be compressed by the end walls of the sockets in the adjacent ends 10 of the tubular sections —1'— and —3'— until the convolutions are brought into close proximity and expanded against the frictional surfaces —11'— and —14'— whereby the rod and tube may be relatively turned in 15 one direction and prevented from turning in the opposite direction as previously described.

The periphery of the several convolutions of the spring —13'— are, in this instance, 20 flattened transversely to form better gripping surfaces for engaging the friction faces —11'— and —14'—.

In using this device, a quantity of hair is tied together near the scalp by means of a 25 cord and the ends of this cord are inserted in the slot —5— of the head —2— to hold it in place for further use, after which the strands of hair which are tied together are wound spirally around and along the tube 30 —1'— or the tubular sections —1'— and —1" — and firmly tied by the cords in place upon said tubes.

Following this operation, the heads —2— and —3— and their connecting rod —1— or 35 the heads —2— and —3'— with their connecting rod sections —4'— and —4" — may be turned relatively to the tube —1— or to the tubular sections —1'— and —1"— for 40 stretching the hair and tightening it upon the tube or if desired, the tube may be turned relatively to the rods and heads to effect a similar tight winding of the hair thereon.

When the bunch of hair has been properly 45 tightened and stretched upon the tube, it may be treated in any well known manner to retain the curl or wave produced by the winding and stretching thereof upon the tube.

50 When the curling or waving operation is completed, the rod with the heads thereon and tube may be relatively turned to loosen the winding of the hair thereon thus permitting it to be withdrawn from the smaller 55 end of the tube and from the head —2— it being understood that the object of the taper of the tube is to facilitate this removal with a slight amount of relative rotation of the rod and tube.

60 In Figures 1 to 4 inclusive, the periphery

of the head —3— is preferably knurled to facilitate its rotary adjustment by hand while in Figures 5 to 7 inclusive, the outer end of the sleeve —3'— may be turned by hand or by the application of a suitable tool 65 thereto.

I claim:

1. In a hair curling device of the character described, a tubular section, end sections 70 engaging opposite ends of the tubular section and rotatable in one direction relatively thereto, said tubular section and one of the end sections having inner annular friction faces, and means frictionally engaging both of said annular friction faces for preventing the relative rotation of the corresponding sections in the opposite direction.

2. In a hair curling device of the character described, a tubular section, end sections 80 engaging opposite ends of the tubular section and rotatable in one direction relatively thereto, said tubular section and one of the end sections having inner annular friction faces, means within the tubular section for transmitting rotary motion from one end section to the other end section, and means frictionally engaging both of said faces for preventing relative rotation of the corresponding sections in the opposite direction. 85

3. In a hair curling device of the character described, a tubular section, end sections 90 engaging opposite ends of the tubular section and rotatable in one direction relatively thereto, said tubular section and one of the end sections having inner annular friction 95 faces, means within the tubular section for transmitting rotary motion from one end section to the other, and a coil spring frictionally engaging both of said faces by its own tension for preventing relative rotation of the corresponding sections in the opposite direction. 100

4. In a hair curling device of the character described, a tubular section, end sections 105 engaging the opposite ends of the tubular section and rotatable relatively to the tubular section, a bolt within the tube and connecting the end sections for transmitting motion from one end section to the other, one of the end sections and the adjacent 110 end of the tubular section being provided with inner annular friction faces, and a coil spring expanding against and frictionally engaging both of said faces to permit said relative rotation in one direction and to 115 prevent the relative rotation in the opposite direction.

In witness whereof I have hereunto set my hand this 18th day of March, 1924.

OSCAR C. KAVLE.
